UNITED STATES PATENT OFFICE.

FERNANDO ARENS, OF HAMBURG, GERMANY.

PROCESS FOR LINING METAL TUBES, PIPES, AND THE LIKE.

No Drawing.

Application filed December 29, 1921. Serial No. 525,601.

To all whom it may concern:

Be it known that I, FERNANDO ARENS, a citizen of the Republic of Brazil, residing at Schwanenwick 28, Hamburg, Germany, have 5 invented a certain new and useful Process for Lining Metal Tubes, Pipes, and the like, for which I have filed applications in Germany Dec. 27, 1920, No. A, 34,620, and in Great Britain, Dec. 13, 1921, No. 33,545, and 10 of which the following is a specification.

This invention relates to a process for producing pipes, tubes and the like the interior of which are coated with a protective material. The process is carried out as follows:

The metal pipe or tube, which is manufactured by the use of centrifugal force, is rotated and liquid or half-set material is then introduced into the interior of it, the material being such that it has the property of 20 hardening on drying and uniting with the rotating metal pipe.

The effect of the centrifugal action is that the liquid or half-set material (for example 25 cement or concrete) is forced against the rough interior of the metal pipe and becomes closely united therewith into a single whole. The process depends upon the con-

dition that the interior of the pipe, made by centrifugal force, has a rough surface. If 30 the liquid or half-set material is pressed by centrifugal force against the inner surface whilst the liquid in the mass escapes an indestructible union between the inner and outer layer is formed. The outer layer can 35 be made very thin and the resulting product is a pipe or tube which is particularly suitable for conducting liquids, for drainage purposes, or for carrying off any kind of chemical waste product, the pipe or tube being 40 reliably free from rust and having a flat uniform and smooth inner surface and finally an almost unlimited life.

What I claim is:—

The herein-described method of making 45 composite pipes which consists in forming a relatively thin outer metallic shell by centrifugal casting whereby a roughened interior wall of fine texture is produced, and introducing a plastic lining material into the 50 shell while rotating the latter whereby to centrifugally mold the plastic material as a lining within the shell and intimately with the roughened inner surface of the shell.

FERNANDO ARENS.
